REFILL FUSE PLUG

John Cree, Hamilton, Ontario, and Frank Corlett,
Crowland, Ontario, Canada, assignors of one-
third to Earle T. Bradfield, Hamilton, Ontario,
Canada

Application September 22, 1938, Serial No. 231,240

6 Claims. (Cl. 200—130)

Our invention relates to improvements in refill fuse plugs and an object of the invention is to provide an improved construction facilitating the disassembling and reassembling of the plug so that a new fuse element may be inserted when the preceding one has been blown out.

A further object is to devise a refill fuse plug in which the electrical contact of the various parts will be substantially as good as in the orthodox non-refillable fuse plug.

A still further object is to provide a lock for the metallic screw shell of the plug so that the latter will not become disengaged from the screw of the insulating body of the plug during the unscrewing of the plug from the metallic screw shell of the fuse block or holder.

With the above and other objects in view which will hereinafter appear as the specification proceeds, our invention consists in its preferred embodiment, of the construction and arrangement all as hereinafter more particularly described and illustrated in the accompanying drawing in which—

Fig. 1 represents a vertical section through a fuse holder of the screw shell type showing our refill fuse plug screwed thereto.

Fig. 2 is a side view of our plug taken at right angles to Fig. 1.

Fig. 3 is a vertical section of our plug taken on the line 3—3 (Fig. 1), the plug being removed from the fuse holder.

Fig. 4 is a vertical section taken on the line 4—4 (Fig. 2).

Fig. 5 is an inverted plan view of our plug.

Figs. 6 and 7 are respectively side and inverted plan views of the insulating body of the plug.

Figs. 8, 9, and 10 are respectively side, plan and inverted plan views of the capsule inserted into the body of the plug and supporting the fuse element, and

Fig. 11 is a plan view of the fuse element.

Like characters of reference indicate corresponding parts in the different views of the drawing.

Our refill fuse plug comprises an exteriorly screw threaded cylindrical body 1 preferably composed of heat resisting glass with a peripheral flange 2 (by means of which the plug is screwed into and unscrewed from the fuse holder) at its closed end which is of reduced thickness to constitute a window 3 for the inspection of the fuse element. The other end of the cylindrical body is open and its lip is provided with a notch 4.

The capsule 5 of insulating material such as porcelain is generally cylindrical in shape and has a circumferential flange 6 therearound intermediate of its length with a lug 7 formed on the upper face of such flange and adapted to be received into the notch 4 when the capsule is in-

serted into the interior of the body 1 with the flange 6 resting on the lip thereof. The upper part 8 of the capsule wall has a flat external groove 9 at one side registering at its lower end with a slot 10 extending through the flange 6, and at the other side a vertical slot 11 extending down from the upper end of the upper part of the capsule to the vicinity of the flange.

The lower part 12 of the capsule has a flat face 13 at one side bevelled off at its free end and a central electrical contact 14 extends axially through the lower end of the lower part of the capsule and is riveted to the offset lower end 15 of a conducting post 16 which extends up into the slot 11 and supports one end of the fuse element 17 which is forked and straddles a set screw 18 in the upper extremity of the post 16. The fuse element 17 extends from the post 16 diametrically across the upper end of the capsule, through a notch 19 and down in the groove 9, through the slot 10 in the flange 6, its other end 20 being turned over outwardly to abut the lower face of the flange 6.

The metallic screw shell 21 having an inturned flange 22 at its outer end defining a central circular opening to receive the lower part of the capsule is threaded onto the body 1 until its flange 22 abuts the flange 6 of the capsule and makes electrical contact with the end 20 of the fuse element 17, a slight protuberance 23 being formed on the upper face of the flange 22 to make better contact between flange 22 and fuse element end 20.

In order to prevent the metallic screw shell 21 from unscrewing itself from the body 1 when the plug is unscrewed from the metallic screw shell 24 of the fuse block or holder 25, a lock plate 26 adapted to lie on the flange 22 of the screw shell 21 and pivoted at one end thereto has its inner edge straight abutting the flat face 13 of the lower part of the capsule and its outer edge arcuate so as to register with the peripheral edge of the screw shell 21. So long as the screw shell 21 is disposed in the screw shell 24 of the fuse block or holder 25, the latter shell will retain the lock plate 26 in engagement with the flat face 13 on the lower part of the capsule and consequently the screw shell 21 will be prevented from turning relatively to the body 1. However, upon the plug being removed from the fuse block or holder, the lock plate will be ineffective to hold the screw shell 21 in position and it may be unscrewed from the body 1, the capsule 5 then being removed and the blown fuse replaced by a new one.

In replacing the fuse element it is only necessary to attach the forked end of the new fuse element to the post by the set screw 18, then bend the fuse element diametrically across the top of the capsule into the notch 19 and down into the groove 9 pushing the free end 20 through the

slot 10 in the flange 6 and bending it outwardly against the lower face of the capsule flange 6 wherein it contacts the flange 22 of the screw shell 21 when the capsule has been inserted into the body 1 and the screw shell 21 has been threaded thereover. The lock plate 26 is then swung inwardly until its straight inner edge abuts the flat face 13 on the lower part of the capsule when the plug is ready for insertion into the fuse block or holder.

The bevel on the flat face 13 on the lower part 12 of the capsule 5 facilitates the bending over of the end 20 of the fuse element 17 by permitting the insertion of a finger nail or thin instrument between such flat surface 13 and the inner face of the end 20 of the fuse element.

What I claim as my invention is:

1. A refill fuse plug comprising an externally threaded hollow body of insulating material open at one end, a hollow fuse element carrying capsule of insulating material open at one end and having a peripheral flange extending therearound intermediately of its length with a fuse element receiving slot therethrough in proximity to the outer wall of the capsule, the open ended portion of the capsule being inserted into the body with the flange abutting the open end thereof, a contact post extending longitudinally in the interior of the capsule, a central contact extending through the outer end of the capsule and secured to one end of the contact post, a continuous integral fuse element detachably secured at one end to the other end of the contact post and extending diametrically across the open end of the capsule and downwardly along its outer wall with the other end of such continuous integral fuse element protruding through the slot in the flange and bent outwardly against the lower surface of such flange, a screw threaded shell of conducting material with an inwardly turned flange defining a central opening receiving the outer portion of the capsule, said shell being screwed onto the screw threaded body with its flange in abutment with the flange on the capsule and such screw threaded shell flange making electrical contact with but mechanically unsecured to the outwardly bent end of the fuse element lying against the flange of the capsule, and means for locking the screw threaded shell against rotation relatively to the body only when the plug is being unscrewed from the screw threaded shell of a fuse block or holder.

2. A refill fuse plug comprising an externally threaded hollow body of insulating material open at one end, a hollow fuse element carrying capsule of insulating material open at one end and having a peripheral flange extending therearound intermediately of its length with a fuse element receiving slot therethrough in proximity to the outer wall of the capsule, the open ended portion of the capsule being inserted into the body with the flange abutting the open end thereof, a contact post extending longitudinally in the interior of the capsule, a central contact extending through the outer end of the capsule and secured to one end of the contact post, a continuous integral fuse element detachably secured at one end to the other end of the contact post and extending diametrically across the open end of the capsule and downwardly along its outer wall with the other end of such continuous integral fuse element protruding through the slot in the flange and bent outwardly against the lower sur-

face of such flange, a screw threaded shell of conducting material with an inwardly turned flange defining a central opening receiving the outer portion of the capsule, said shell being screwed onto the screw threaded body with its flange in abutment with the flange on the capsule and such screw threaded shell flange making electrical contact with but mechanically unsecured to the outwardly bent end of the fuse element lying against the flange of the capsule, a flat side on the outer portion of the capsule, and a swingable locking plate mounted on the flange of the screw threaded shell and engageable with said flat side of the outer portion of the capsule for locking the screw threaded shell against rotation relatively to the body when the plug is being unscrewed from the screw threaded shell of a fuse block or holder.

3. In a refill fuse plug, in combination, an externally threaded hollow body of insulating material open at one end, a fuse element carrying capsule of insulating material inserted into such body with one end protruding therefrom, a screw threaded shell screwed onto the body for holding the capsule therein, and means for locking the screw threaded shell against rotation relatively to the body only when the plug is being unscrewed from the screw threaded shell of a fuse block or holder.

4. In a refill fuse plug, in combination, an externally threaded hollow body of insulating material open at one end, a fuse element carrying capsule of insulating material inserted into such body with one end protruding therefrom, a screw threaded shell screwed onto the body for holding the capsule therein, a flat side on the protruding end of the capsule, and a swingable locking plate on the screw threaded shell engageable with the flat side of the protruding end of the capsule for locking the screw threaded shell against rotation relatively to the body when the plug is being unscrewed from the screw threaded shell of a fuse block or holder.

5. The invention claimed in claim 4 wherein the screw threaded shell has an inwardly turned flange defining a central opening through which the protruding end of the capsule extends, and such swingable locking plate is mounted on such flange.

6. The combination with the screw threaded shell of a fuse block or holder, of a refill fuse comprising an externally threaded body of insulating material open at one end, a fuse element carrying capsule of insulating material inserted into such body with one end protruding therefrom, a screw threaded shell screwed onto the body for holding the capsule therein, said screw threaded shell having an inturned flange defining a central opening receiving the protruding end of the capsule, a flat side on the protruding end of the capsule, a swingable locking plate on the flange of the screw threaded shell having a straight inner edge engageable with the flat side on the protruding end of the capsule, and a curved outer edge conforming with the peripheral curvature of the shell whereby the locking plate is held in engagement with the flat side of the protruding end of the capsule when the plug is located in the screw threaded shell of the fuse block or holder.
